PROGRAM PRESELECTING RADIO
CONTROL UNIT

Freeman H. Owens, New York, N. Y.

Application June 10, 1941, Serial No. 397,504

9 Claims. (Cl. 250—20)

The invention here disclosed relates to apparatus for preselecting desired programs or sequences and for controlling the mechanism necessary for effecting the sequences of events so selected.

Particular objects of the invention are to provide a device of the character mentioned, which will be of a simple inexpensive structure, compactly put together, small in size and made up of parts readily manufactured and easy to assemble.

Other special objects are to provide a control unit of the character specified, which may be readily connected and used with different radio receiver and phonograph units and the like, and the operation of which will be readily understandable to those accustomed to such devices.

A further important object of the invention is to provide in a device of the character mentioned, simple and practical means for recording the programs actually selected by the instrument.

Additional objects of the invention are to provide apparatus of the character specified, which will be of rugged sturdy design, not liable to get out of order and not subject to servicing needs or the like.

Other important objects of the invention will appear as the specification proceeds.

The novel features and combinations through which the purposes of the invention are attained are set forth in the following specification, broadly covered in the claims and illustrated by way of practical example in the accompanying drawings. It is realized however, that actual physical structure may be modified and changed in various ways all within the true intent and broad scope of the invention. The illustration therefore is to be considered primarily for purposes of disclosure and not by way of limitation, the scope of the invention being as hereafter broadly defined and claimed.

Fig. 1 is a front elevation of a control unit embodying the invention, designed for twenty hour service, automatic program selection for six different radio stations and phonograph, under preselected volume, also manual or arbitrary station and phonograph selection and arbitrary tuning to other radio stations, at desired volume.

Fig. 2 is a broken vertical and transverse sectional view as on substantially the line 2—2 of Figs. 1 and 3.

Fig. 3 is a broken longitudinal sectional view substantially as on line 3—3 of Fig. 2.

Fig. 4 is a broken sectional detail of the timing

shaft mechanism on substantially the plane of line 4—4 of Fig. 1.

Fig. 5 is a broken sectional detail of one of the electromagnetic switch mechanisms, on substantially the line 5—5 of Fig. 3.

Fig. 6 is a broken part sectional view on substantially the plane of line 6—6 of Fig. 5.

Fig. 7 is a broken sectional detail of the manual interlock mechanism on substantially the plane of line 7—7 of Figs. 1 and 3.

Fig. 8 is a broken sectional detail of switch and volume control mechanism on substantially the plane of line 8—8 of Fig. 3.

Fig. 9 is a broken longitudinal vertical sectional view as on substantially the plane of line 9—9 of Fig. 2.

Fig. 10 is a sectional detail of the switch rocker mechanism substantially on line 10—10 of Fig. 9.

Fig. 11 is a broken vertical sectional view of 20 the recorder, located to the rear of the time shaft mechanism shown in horizontal section in Fig. 4, this view Fig. 11, being taken substantially as on line 11—11 of Fig. 12.

Fig. 12 is a broken part sectional view of the 25 recorder mechanism as viewed in the direction of the arrow 12, Fig. 11.

Fig. 13 is a broken part sectional detail view of the recorder mechanism, as on substantially the plane of line 13—13, Fig. 12.

Fig. 14 is a broken sectional detail of the record 30 roll gearing as on substantially the plane of line 14—14 of Fig. 12.

Fig. 15 is a broken plan of a typical record strip.

Fig. 16 is a general wiring diagram.

Fig. 17 is a diagram in somewhat more detail 35 to show connections through the station selection time switches.

Fig. 18 is a broken front elevation of the magnetically operated switch actuating and latching 40 means.

Fig. 19 is a perspective view of the latch for holding the power switch closed.

Fig. 20 is a part sectional perspective view of the universal latch bar.

Fig. 21 is a perspective view of one of the 45 switch closing push levers.

In the form of the invention here disclosed, selection of the stations or the phonograph, to be brought in at desired broadcast periods, is 50 effected by picking out keys or levers representing time or broadcast periods, in a bank of such keys or levers, and setting them accordingly to different radio station or phonograph positions.

In Fig. 1, the bank of station selecting time 55 keys is indicated at 20, and as this particular

machine is designed for twenty hour operation, as from 6 o'clock in the morning to 2 o'clock at night, there are 80 such keys, four to each hour, for the present 15 minute broadcast periods.

To readily identify the different time keys, an hour scale 21, is placed below the keys, broken up above, into 15 minute scales 22, in register with the individual keys.

At the ends of the bank of keys, the station and phonograph positions are indicated at 23, there being six radio station positions and one phonograph position shown.

While a single tuning mechanism may be employed and adjusted each time a change is made from one station to another, in the present disclosure, a separate tuner is provided for each station and adjusted each to a particular station, so that such stations can then be brought in by simple switching operations.

Thus in the illustration, for the six stations, there are six tuning controls 24, each of which is set for a particular station and then left at that setting so as to bring in the station to which it is tuned by a simple circuit closing operation.

Similarly, while it is possible to provide a single volume control and adjust that to the desired sound level, as may be required, there is provided in the present disclosure, a volume control 25, for each tuned circuit, which can be set for the particular sound level desired for a particular station and then left at that setting, being cut into effect each time the station is brought in.

In Figs. 2 and 3, the bank of keys is shown as made up of a bank of cam-like discs strung together in side-by-side relation on a supporting rod 26, having reduced end portions 27, dropped into notches 28, in the upper ends of supporting brackets 29. Insulating spacers 30, at the ends of the bank hold the keys properly registered with the switch fingers which they operate.

The thus rotatably supported keys are shown in Fig. 2, as having operating handles 31, projecting through the case 32, of the instrument and as having cam projections 33, to depress the arched spring contact fingers 34, of longitudinally extending bus bar strips 35, into engagement with terminal lugs 36, of the segment strips 37.

The spring switch fingers 34, may be formed integrally with the longitudinal bus bars 35, in the nature of a comb construction, each constituting a multiple switch contact terminal for a particular radio station or phonograph, as so marked in Fig. 2, on the wiring lugs 38, at the ends of the same.

The segments 37, extend transversely at the back of and in register with the operating keys, one for each broadcast period, with switch lugs 38, of that particular time in register with the switch fingers of the different radio stations and phonograph, said segments having wiring terminals 39, at the ends of the same.

The station representing combs are shown mounted on the inner face of a curved sheet of insulating material 40, and the time segments on the back of such insulating base, with the lugs 38, projecting through to the inner face of the base, between the bus bars, in position to be engaged by the spring fingers. The curved insulating base is shown in Fig. 9, as supported at the ends by the same brackets 29, which support the key shaft 26.

Spring detents 41, forming integral parts of a comb strip 42, engage in notches 43, to hold indi-

vidual keys in positions to which they are adjusted.

The actual timing is provided in the disclosure by an electric clock 44, which is shown in the diagrammatic views, Figs. 16, 17, as connected directly across a standard supply circuit 45, and as operating a 15 minute or broadcast period cam 46, to control a lever 47, which at the end of each broadcast period closes the circuit at 48, through an electromagnet 49.

The magnet 49, is connected by wires 50, 51, across the secondary 52, of a transformer, the primary 53, of which is connected by wiring 54, with the service circuit.

Interposed in the primary circuit 54, is a mercury switch 55, carried by a rocker 56, Figs. 9 and 10, pivoted on stud 57, and having a pin 58, entered in a notch 59, in the slide 60, which is guided at 61, over the stud 57, and at 62, over a reduced portion 63, of a time shaft 64.

The core 65, of solenoid magnet 49, is connected at 66, with the upper end of slide 60, so that said slide is lifted for each broadcast period.

The raising of slide 60, rocks the mercury switch 55, and to interrupt the primary circuit of the transformer, but before this circuit is broken, an impulse is sent out by reason of the closure of the secondary circuit at 48, along the wires 50-57 to a stationary contact ring 68, engaged by a brush 69, to carry current to one of two ring segments 70, 71, the first of which is connected at 72, with an outer ring 73, engaged by brush 74, to carry current to one of a surrounding series of time terminals 75, and the other of which is connected at 76, to a ring 77, Fig. 16, engaged by brush 78, to carry current to one of a second series of time contacts 79.

By breaking the set of eighty time contacts up into two circular series, a better spacing of the terminals is accomplished in a smaller diameter, taking up less space than would be required in a single circular series. The outer distributor rings 73, 77, are shown notched at 80, in line with the contact points 75 and 79, to aid proper registry of the brushes 74 and 78.

The distributor brushes 74 and 78, as shown in Fig. 4, are mounted on opposite faces of an insulating carrier 81, keyed at 82, on the timing shaft 84, the first to engage ring 73, and terminals 75, on an insulating support 83, and the other to engage the ring 77, and the wire terminals 79, on insulating support 82a.

The brush 69, of the changeover switch is carried by an insulating support 84, on sleeve 85, rotatably mounted on the same shaft and driven at half shaft speed by the attached gear 86, which as indicated in Fig. 6, is engaged by a pinion 87, operating on center 88, and having connected with it a gear 89, in mesh with a pinion 90, fixed to the ratchet 91, which is keyed on the shaft at 92.

A spring pressed driving pawl 93, engages ratchet 91, said pawl being mounted on a pivot pin 94, carried by a yoke 95, pivoted to rock on shaft 84.

As shown in Figs. 4 and 9, the pawl carrying stud 94, projects through an arcuate slot 96, in the shaft supporting wall 97, at the front and projects at the rear into a notch 98, in the magnet operated slide 60.

Step-by-step rotation is thereby imparted to the time shaft, an amount sufficient to carry the brushes 74 and 78, to the next contacts 75, 79, at the end of each 15 minute interval and these in-

ermittent movements at the end of a 12 hour period, through the half time gearing are sufficient to carry the changeover brush 69, from one contact segment 70 or 71, over onto the other segment, thus to switch circuit control over from one set of time contact points 75 or 76 to the other.

Retrograde movement of the timing shaft is prevented by a spring pressed holding pawl 88, shown in Fig. 6, as engaging ratchet 81.

The time shaft makes one complete revolution each 12 hours, in 48 steps. Each section of the two part distributor switch therefore may have 48 distributor points as indicated at the top at 75, Fig. 16, providing the possibility for wiring for the entire 24 hour control.

At the end of a 12 hour run, for instance, from 6 o'clock in the morning to 6 o'clock in the evening, the first 48 contacts may be in service, through the brush 69, connecting segment 70, with the current supply ring 68. At the end of the 12 hour period, that is, in the example at 6 o'clock in the afternoon, the brush 69, travelling at half shaft speed will shift over onto segment 71, as indicated in the broken lines, Fig. 16, thus to carry current over to the second distributor ring 77, and hence at that time through brush 78, onto the 49th contact point of the series designated 79. The circuit then will be continued for the 15 minute intervals through the contacts of this second series up to the 80th contact, corresponding in time to 1:45 A. M., ending the 20 hour run (eighty 15 minute intervals) of the instrument. The eighty-first to the ninety-sixth contacts, if provided on this second series, will then simply serve as idle steps for the distributor brush 78 to ride on.

The contacts 75 and 79, are connected, in the order of sequence, by wires 100, Fig. 17, with the corresponding time switch segments 37, and the switch combs 38, representing stations, are connected by wires 101, with switch closing magnets 102, which are connected by wiring 103, 51, with secondary 52.

The magnets 102, have cores 104, Figs. 5, 6, 7 and 8, connected with levers 105, pivoted on a supporting rod 106, and having portions 107, disposed to push the plungers 108, forwardly to bring the three pairs of switch contacts 109, 110, 111, into engagement as in Fig. 17, to close circuits respectively, by wiring 112, through station indicating lamps 113; by wiring 114, to the preset station tuners 24 and by wiring 115, to the volume controls 25.

The switch closing plungers 108, are locked in the projected switch closing position by a universal latch bar 116, pivoted to swing on the supporting rod 106, and having an angled lower edge 117, operable as a holding dog engageable with the bevelled annular shoulders 118, of the plungers. This universal latch bar, as indicated in Figs. 5 and 6, 18 and 20 is pivoted to swing in front of the several plunger pushing levers 105, so that the actuation of any one of said levers will lift the latch to release a previously projected plunger and permit the same to drop back into the retracted position indicated in Fig. 5, where the dogging edge of the latch will then be received in an idle annular groove 119, in the plunger.

Springs 120, return the individual switch levers 105, to retracted position and the cores of the switch magnets have extensions 121, at the front, carrying handles 122, exposed at the front of the case, by which such switches can be arbitrarily

operated to bring in one of the pretuned stations at any time.

To prevent actuation of more than one switch manual at a time, suitable interlock may be provided between the several switch knobs as indicated in Figs. 5 and 7, which show such means as consisting of two overstanding slides 123, operating in guides 124, and having offset passages 125, therethrough receiving the reduced and bevel 10 shouldered portions 126, of the handle shanks and which passages when aligned will permit switch operating movement of only one handle.

To control "on" and "off" conditions of the device, there is provided what may be considered a power switch, shown in Figs. 2, 16 and 17, as made up of switch contacts 127, in the power circuit 128, of the radio and phonograph set and arranged to be closed by a plunger 129, actuated by a pusher extension 130, Fig. 20 on the end 20 of the universal latch bar 116. Thus each time the latch bar is raised through actuation of any one of the station magnets 102, the power switch will be closed, if previously open, or reclosed, if then in the closed condition.

To hold the power switch 127, closed, a special latch 131 is shown engageable with shoulders 118 and 119, Figs. 8, 17 and 19, in the plunger 128, similar to the correspondingly numbered shoulders in the other switch plungers.

To release the latch 131, and thus open the power circuit to shut off the set, an extra magnet 132, Fig. 2, is provided, for operating a lever 133, carrying said latch 131.

Also shown in Fig. 2, is the extra bus bar comb 134, having switch fingers 135, engageable with the "off" contact lugs 136, at the bottom of switch segments 37, when switch keys 20, are in the upright "off" position. The electrical connections for the "off" magnet are similar to those for magnets 102, as generally indicated in Fig. 17, and this magnet, like the station magnets has a handle 137, by which the set can be turned off at any time.

Details of the individual station tuners 24, are not illustrated, since these units will vary in accordance with the type of tuning used, inductance, capacity, or otherwise. For convenience, the preset station tuning elements are indicated in the diagrammatic view, Fig. 16, as variable condensers 138, and these tuning devices whatever their structure, may have individual dials or the like, as indicated at 139, in Fig. 1.

For tuning the set arbitrarily, as to bring in other than the automatically selected stations at any time, there is provided in the illustration, a special circuit tuning device 140, Fig. 2, having its own tuning dial 141, and control 142. Similarly, this arbitrary or master tuner has its own volume control at 143.

In order that the arbitrary tuning and volume control shall have no effect upon the automatic station selecting operation, both the arbitrary tuner 142, and volume control 143, are automatically returned to a neutral or ineffective position each time a station selection is made, by means of two gear segments 144, 145, Figs. 2, 4, 9, pivoted on the timing shaft 84, above a laterally projecting step or shoulder 146, on the slide 69, and engaging the first, a pinion 147, on the inner end of the volume control shaft 148, and the other a motion reversing gear 149, in mesh with pinion 150, on the inner end of the tuner shaft 151.

Each time the magnet 49, is energized, that is, for each broadcast period, the magnet slide 69,

will pick up the gear segments 144, 145, wherever they may have been left by adjustment of volume at 143, and arbitrarily tuning at 142, to return these elements to the neutral or ineffective positions, where they will not interfere with automatic station selection and volume control.

The volume controls may be of resistance, potentiometer or other types and so are generally represented at 152, Figs. 2, 3, 8 and 16.

In Fig. 1, the volume control of the phonograph is designated 153, and the manual button for cutting in the phonograph at any time is indicated at 154, the latter corresponding in general construction and operation to the station manuals 122.

To show the broadcast period time and to provide a means for setting the instrument to the existing time, the timing shaft 64, is shown as carrying a knob pointer 155, on its front end, travelling over a broadcast time dial 156, which may be translucent and illuminated from within the casing by a lamp 157, Fig. 3.

A record of the use to which the instrument is put, is provided, in the illustration, by a tape 158, Fig. 15, perforated at 159, to receive one or more teeth of sprocket 160, Figs. 10 and 11, attached to roll 161, journaled on stud 162, carried by insulating case 163, which is slipped into the back of the casing to bring the conically recessed toothed end 164, of the roll over the corresponding cone on the end of a drive bushing 165, rotatably engaged at 166, on the rearwardly extending portion of shaft 64. This drive bushing is shown provided with a ratchet 167, engaged by a spring pressed pawl 168, Figs. 4 and 13, on the rearward end of the same stud 64, which carries the time shaft driving pawl 93.

As a consequence, the sprocket 160, will be turned to advance the record tape a distance 169, representing one broadcast period for each station selecting impulse.

Station and phonograph designating electrodes 170 together with a common return connection on electrode 171, are mounted in insulated relation in a yoke-like holder 172, pivoted on a supporting shaft 173, and connected in the corresponding circuits, so that with each impulse there will be a discharge from the electrode representing the selected circuit, down through the tape as at 174, Fig. 15, to the tape carrying roll 161, and by way of the latter back through the tape to the common return, producing the second indicating burn or perforation 175.

By providing an "off" electrode 176, Fig. 13, a third mark will be made on the strip providing a record 177, of the "on" and "off" state of the machine.

The gang of electrodes is automatically lifted off the strip, for each movement of the latter, by projecting the pivot pin 66, of the magnet slide, Figs. 11 and 13, through a slot 178, in the inner arm of the electrode carrying yoke 172.

To raise the electrodes when the record box is to be placed in or removed from the machine, a yoke lever 179, is shown pivoted on supporting shaft 173, the outer arm serving as a handle and the inner arm extending in under the screw projections 180, on the front of the electrode carrier.

As the record tape need move only a slight distance for each broadcast period, a short length of tape will carry a long time record and this in turn means that the record mechanism may be a small unit with simple spooling mechanism for the tape. The latter is shown as consisting simply of two hollow spools 181, 182, slipped over 75

journal projections 183, 184, on the opposite walls of the casing and having gear toothed ends 185, meshing with a pinion 186, journaled on a wall projection 187, between the spools. With this construction, the unwinding spool, through the intermediate pinion, drives the other, as a take-up spool.

The casing is shown made of two parts separable along the line 188, and removably held together by screws 189.

The lever 179, in addition to serving as a means for lifting the electrodes, is shown as dropping down over the front of the record case to hold it up against the yielding stop 190, with the toothed faces 191, of the cone clutch at 164, properly engaged for driving the record roll.

Fig. 16 shows at the right how the gang of three switches 199, 200, 201, for the phonograph control necessary circuits for that instrument and in this view, there is also shown at 192, an electric outlet receptacle which is cut into circuit at the same time with the phonograph and into which a connector 193, such as for a coffee pot, toaster, water heater or the like, may be plugged. This service outlet, under control of the phonograph timing circuit, makes it possible to utilize the machine for any desired time operations and either in conjunction with or, without the phonograph, for operation of the phonograph may be avoided by simply leaving that machine without a record in place.

The service recorder may be locked in place, so that it may not be tampered with, thus to assure an accurate record of the use of the machine. As here shown, the record tape provides an easily readable record of the time the machine has been in service and the stations that have been listened to. The tape may carry a running time indication which then will show the actual times various stations were listened to, thus affording a gage of the comparative popularity of different programs. Special decoding or translating mechanism may be provided for totalizing or summarizing results shown on the record.

The phonograph and service outlet, or either, because of the wide possibility of uses, may be considered as a general utility circuit.

It is to be noted that when the machine has made the station selection, turned on the phonograph or accomplished some other utilitarian purpose, or turned off the controls, according to the setting of the selecting time keys, current through the control parts will be cut off through interruption of the primary circuit at the mercury switch 55, and that for the next 15 minute or broadcast time interval, the only current consumed by the machine will be the slight amount taken by the time clock—that in the primary 53, of the transformer being practically negligible, because of the open circuit condition of the secondary. The mercury switch 55, may be of the slow return type, as indicated in Fig. 16, so as to prevent recurrence of the station selecting operations before the time cam has again broken the initial control circuit at 48.

The magnet for controlling the phonograph circuits is indicated only generally, at 194, Fig. 7, since the organization may be the same as that for the several station selecting switch magnets 102. It will be appreciated also that circuits outlined in Fig. 16, are not in all instances complete, particularly so as different radio receivers and phonograph units will require specifically different connections.

To enable the selector unit to be set to the

correct time in any 15 minute interval, there is provided in the illustration, a setting button 185, Fig. 1, which through a connected pinion 186, within the case, Figs. 16 and 17, can turn the gear 197, which carries the quarter hour cam 46, the latter having a pawl and ratchet connection at 198, with the shaft or arbor 199, of the time clock 44. This mechanism enables the unit to be set to the fractional portions of a quarter hour period and, if it were desired, enables the device to be set so as to come on to different stations or be shut off half way through, or at some other intermediate points in the broadcast periods.

The various tubes and parts of the radio receiving apparatus, other than the pretuned station selecting devices and associated preset volume controls have not been illustrated, since these may vary so widely. Ample space for such parts however is present within the case of the unit, as indicated by the single radio tube indicated at 200, in Fig. 9. The entire radio receiver portion of the apparatus, if desired, may be mounted on a chassis of its own or on a single sub-base, so that such apparatus may be assembled and treated as a unit in itself.

The so-called radio and phonograph unit represented at 201, in Figs. 16 and 17, may carry any necessary power transformers, amplifier and speaker mechanisms, as well as all the phonograph parts.

While different forms of volume controls may be employed, it is preferred at present to construct these as shown in Fig. 2, by winding two lengths of wire about a flat strip of insulation and then coiling the strip and seating it in a circular recess, where the inner turns of the wire can be engaged by the oppositely extending brushes 202. With this construction, as particularly shown in Fig. 16, the resistance may be entirely cut out or cut in up to the full amount.

The magnets may be of the "ironclad" type provided, as shown in Figs. 2, 3, 5 and 7, with a complete metallic casing made up of upper and lower halves 203 and 204, secured in abutting engagement at the front and the back by the mounting screws 205. The pawl and ratchet drive by which the record strip is intermittently advanced enables the record strip to remain stationary when the shaft 26 is turned by the setting knob when setting the device to the proper time.

What is claimed is:

1. A program preselector, comprising a time clock, a broadcast period circuit controller operated thereby, a distributor including a series of successively arranged time contacts and a brush cooperative therewith, means controlled by said circuit controller for effecting step-by-step engagement of said brush with successive time contacts, a bank of corresponding time keys movable to different station selecting positions, time representing switch elements connected with the respective distributor contacts and provided each with a number of different station contacts, station representing buses, switch fingers shiftable by said keys in the different station selecting positions of the same into positions connecting the respective bus bars and different station contacts, different station control circuit means operatively connected with the respective buses, said means controlled by said broadcast period circuit controller, including a power circuit having a circuit interrupter of the slow return type therein and said different station control circuit means including station tuning circuits supplied from said power circuit.

2. A program preselector, comprising a time clock, a broadcast period circuit controller operated thereby, a distributor including a series of successively arranged time contacts and a brush cooperative therewith, means controlled by said circuit controller for effecting step-by-step engagement of said brush with successive time contacts, a bank of corresponding time keys movable to different station selecting positions, time representing switch elements connected with the respective distributor contacts and provided each with a number of different station contacts, station representing buses, switch fingers shiftable by said keys in the different station selecting positions of the same into positions connecting the respective bus bars and different station contacts, different station control circuit means operatively connected with the respective buses and radio station selective means operable independently of control exercised by said time keys, said different station control circuit means including electromagnets and armatures operated thereby and said radio station selective means including manuals arranged to directly and arbitrarily actuate said armatures independently of the magnets which may normally actuate the same.

3. A program preselector, comprising a time clock, a broadcast period circuit controller operated thereby, a distributor including a series of successively arranged time contacts and a brush cooperative therewith, means controlled by said circuit controller for effecting step-by-step engagement of said brush with successive time contacts, a bank of corresponding time keys movable to different station selecting positions, time representing switch elements connected with the respective distributor contacts and provided each with a number of different station contacts, station representing buses, switch fingers shiftable by said keys in the different station selecting positions of the same into positions connecting the respective bus bars and different station contacts, different station control circuit means operatively connected with the respective buses, including pretuned station selecting devices and switches for selectively cutting the same into and out of operative condition, an arbitrarily operable station tuning device and means for automatically returning the latter to a neutral condition upon initiation of automatic station selecting operations.

4. A program preselector, comprising a time clock, a broadcast period circuit controller operated thereby, a distributor including a series of successively arranged time contacts and a brush cooperative therewith, means controlled by said circuit controller for effecting step-by-step engagement of said brush with successive time contacts, a bank of corresponding time keys movable to different station selecting positions, time representing switch elements connected with the respective distributor contacts and provided each with a number of different station contacts, station representing buses, switch fingers shiftable by said keys in the different station selecting positions of the same into positions connecting the respective bus bars and different station contacts, different station control circuit means operatively connected with the respective buses, including station selecting devices and switches controlling the same and preset volume controls for said different pretuned station selecting devices, arbitrary tuning and volume control means and means for automatically returning said arbi-

trary tuning and volume control means to neutral condition upon initiation of automatic station selecting operations.

5. A program preselector, comprising a time clock, a broadcast period circuit controller operated thereby, a distributor including a series of successively arranged time contacts and a brush cooperative therewith, means controlled by said circuit controller for effecting step-by-step engagement of said brush with successive time contacts, a bank of corresponding time keys movable to different station selecting positions, time representing switch elements connected with the respective distributor contacts and provided each with a number of different station contacts, station representing buses, switch fingers shiftable by said keys in the different station selecting positions of the same into positions connecting the respective bus bars and different station contacts, different station tuning control circuit means operatively connected with the respective buses, a power source, a transformer having a primary winding connected with said power source and controlled by said means controlled by said time clock operated circuit controller, and said transformer having a secondary connected with said circuit controller and with said distributor.

6. A program preselector, comprising a time clock, a broadcast period circuit controller operated thereby, a distributor including a series of successively arranged time contacts and a brush cooperative therewith, means controlled by said circuit controller for effecting step-by-step engagement of said brush with successive time contacts, a bank of corresponding time keys movable to different station selecting positions, time representing switch elements connected with the respective distributor contacts and provided each with a number of different station contacts, station representing buses, switch fingers shiftable by said keys in the different station selecting positions of the same into positions connecting the respective bus bars and different station contacts, different station tuning control circuit means operatively connected with the respective buses, including electromagnetic circuit closers connected respectively with the station representing buses, manuals for arbitrarily operating said electromagnetic circuit closers and means

for limiting operation of said manuals to one at a time.

7. In combination, a broadcast receiver having separate pretuned station controls and associated separate preset volume controls, timing mechanism for selectively rendering the same effective at different preselected times for preselected periods of time and means for arbitrarily rendering any pretuned station selector and volume control effective at any time.

8. In combination, pretuned station selecting devices, a preset volume control associated with each pretuned station selecting device, switches for rendering said station selecting devices, and volume controls effective and timing mechanism including means for selectively closing said switches at preselected times and for preselected periods, means for arbitrarily tuning and controlling volume and means automatically operable to return said arbitrarily operable tuning and volume controlling means to an ineffective condition on operation of said timing mechanism.

9. A program preselector, comprising a time clock, broadcast timing means operated by said time clock, a distributor including successively arranged time contacts and a brush successively cooperative therewith, time representing switch elements connected with the corresponding time contacts of said distributor, station representing buses, time keys corresponding to the different broadcast time periods and movable to effect connection of the corresponding time representing switch elements with different selected station representing buses, different station control circuit means operatively connected with the respective buses, including pretuned station selecting devices and a preset volume control associated with each pretuned station selecting device and electromagnetic means for rendering preselected, pretuned station selecting devices and associated preset volume controls effective at times selected by said time keys, said electromagnetic means including electromagnets and armatures operated thereby and manuals for effecting arbitrary actuation of said armatures independently of the control exercised by said timing means and distributor.

FREEMAN H. OWENS.
